UNITED STATES PATENT OFFICE.

FRANK A. OSTERBERG, OF CHICAGO, ILLINOIS.

SERVING-TABLE.

1,380,007.

Specification of Letters Patent. Patented May 31, 1921.

Application filed April 3, 1920. Serial No. 371,020.

To all whom it may concern:

Be it known that I, FRANK A. OSTERBERG, a citizen of the United States, residing at Chicago, county of Cook, State of Illinois, 5 have invented a certain new and useful Improvement in Serving-Tables, and declare the following to be a full, clear, and exact description of the same, such as will enable others skilled in the art to which it pertains to make and use the same, reference being had to the accompanying drawings, which form a part of this specification.

My invention has for its object to produce a simple and novel table which may 15 be projected over a bed to support food or other things, be wheeled bodily away from the bed and, when not in use, be folded into a compact form.

The various features of novelty whereby 20 my invention is characterized will herein-after be pointed out with particularity in the claims; but, for a full understanding of my invention and of its object and advantages, reference may be had to the following detailed description taken in connection with the accompanying drawings, wherein:

Figure 1 is a side elevation of a table arranged in accordance with a preferred form of my invention, opened and ready 30 for use;

Fig. 2 is a front elevation of the table looking at the left hand end of Fig. 1;

Fig. 3 is a vertical section taken approximately on line 3—3 of Fig. 2;

Fig. 4 is a front elevation of the table in its folded condition;

Fig. 5 is a section taken approximately on line 5—5 of Fig. 4;

Fig. 6 is a section taken approximately 40 on line 6—6 of Fig. 4; and

Fig. 7 is a sectional detail on an enlarged scale showing the sliding connection between the table leaf and the supporting standard.

Referring to the drawings, 1 and 2 represent 45 two upright members connected together by cross pieces, 3 and 4, in the vicinity of the ends thereof, thus forming an approximately rectangular frame. In the inner edges or faces of the uprights are longitudinal grooves, 5. 6 is a table leaf having in the vicinity of one end thereof an underlying transverse rod, 7, secured thereto by

clips, 8, or otherwise, so that the rod may rotate; the ends of the rod projecting laterally beyond the leaf and being bent or shaped into or having thereon shoes, 9, fitting slidably into the grooves 5. On the under side of the table leaf, near and parallel with the side edges thereof, are arranged two long rods, 10, secured to the leaf by means of bearing devices, 11, which permit the rods to rotate while holding them against endwise movement. Each of the rods 10 has at the inner end an arm, 12, bent approximately at right angles thereto, the free end of the arm 12 being again bent laterally as indicated at 13, so as to lie approximately parallel with the main portion of the rod. The rod, 7, serves as a sliding hinge support for one end of the table leaf while bent rods serve as brackets to hold the table in a horizontal position or permit the leaf to swing down within the frame-like standard. It will be seen that when the bent rods are turned so as to bring the parts 12 and 13 thereof flat against the under side of the leaf, as illustrated in Figs. 4, 5 and 6, the leaf may be swung down against the supporting standard, the hinged end having first been raised high enough to permit this. When the bent rods are swung outwardly as illustrated in Figs. 1 and 2, so that the members 13 thereof abut against the uprights 1 and 2 of the supporting frame, the leaf will be held at right angles to the supporting standard, that is horizontal. If the bent rods simply abutted against the uprights they would not prevent the table leaf from dropping down bodily and therefore I have provided each upright with a series of upwardly directed shoulders, distributed along the same, these shoulders being in the form of holes, 14, and being so positioned and of such a size that the parts 13 of the bent rods may be inserted in corresponding holes of each series so as to support the table leaf at any one of a plurality of different elevations.

On the under side of the leaf is a drawer, 15, supported in suitable guides, 16, so as to permit the drawer to be positioned wholly underneath the leaf as shown in full lines in Fig. 1 or be drawn outwardly as shown in dotted lines in this same figure,

In order to maintain the supporting standard in an upright position and permit the table as a whole to be moved about freely, I have hinged the uprights, at their lower ends, to one end of a low wheeled truck, 17; the hinges being shown at 18. The truck carries two arms or bars, 19, each hinged at one end to the truck, as indicated at 20, at some distance from the hinges 18. These arms or bars may be swung down so as to lie below the top surface of the truck as indicated in dotted lines in Fig. 3 and in full lines in Fig. 5, or they may be swung upwardly so that each will extend diagonally between the top of the truck and one of the uprights. In the arrangement illustrated, as best shown in Fig. 3, each of the uprights is provided with a stop or pin, 21, on which the free end of the corresponding bar or arm, 19, may rest when swung upwardly, and the transverse bar or connecting piece, 4, is provided with downwardly and forwardly-opening pockets, 22, just above the pins 21, to form seats for the upper ends of the arms or bars. When the table is opened ready for use as illustrated in Fig. 3, the arms or bars, 19, serve as struts or braces which will prevent the supporting standard from tilting forward under the weight of a load on the table leaf. The standard may be prevented from swinging in the opposite direction by means of a simple hasp or shackle device, 24, conveniently such as commonly employed on suit cases, arranged between the lower end of each upright and the adjacent portion of the truck.

When the table is to be used, it is opened up as shown in Figs. 1, 2 and 3, the leaf being placed at any desired elevation to suit the conditions under which it is to be used, and the table as a whole may be wheeled about from one point to another. When the table is not in use it may be folded into a compact form and stored away; the user simply swinging the leaf upwardly through a sufficient angle to carry the ends, 13, of the bent rods out of the holes; the bent rods being then swung so as to lie flat against the under side of the leaf; the leaf being then swung down so as to lie within the frame-like standard between the cross bars 3 and 4; the holding devices, 24, being disengaged and the bars 19 being swung down into the position shown in dotted lines in Fig. 3; and the truck being then folded up flat against the standard as shown in Figs. 4, 5 and 6.

After the parts have been folded together, the swinging end of the table leaf may be locked to the standard by means of small plates, 25, lying on the under side of the leaf, near its free end and pivoted intermediate their ends to the leaf. When the table is in use these plates are swung around so

as to be concealed beneath the leaf but, when the table is opened, they are turned through an angle of ninety degrees into the positions illustrated in Fig. 4, their outer ends extending into the grooves 5 in the standard. The truck may be held folded against the standard by means of hooks, 26, one of which is secured to each of the uprights, and eyes, 27, on the truck; the hooks being entered into the eyes when the parts are folded together, and locking them together.

If desired, the bounding walls of the grooves, 5, may be cut away in the rear at their extreme upper ends, so as to permit the shoes on the ends of the hinge rod for the table leaf to be inserted laterally; the cutting away of these walls forming a gap as indicated at 28 in Fig. 2.

The cross piece, 3, of the supporting standard will usually lie at some distance above the table leaf when the table is opened, and will serve as a rack on which towels, napkins, or other articles may be hung.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. A serving table comprising a standard in the form of a frame open in the center and having grooves extending lengthwise of the upright members of the frame on the sides facing each other, a table of a size and shape such that it may lie flat within the opening in the standard, said leaf having at one end lateral projections entered into said grooves and permitting the leaf to swing into and out of said opening and to move bodily along said upright members, brackets secured on the under side of said leaf and movable from positions in which they lie flat against the latter to positions in which they extend downwardly, and shoulders distributed along said uprights in position to engage said brackets when the latter extend downwardly from the leaf.

2. A serving table comprising a standard in the form of a frame open in the center and having grooves extending lengthwise of the upright members of the frame on the sides facing each other, a table of a size and shape such that it may lie flat within the opening in the standard, said leaf having at one end lateral projections entered into said grooves and permitting the leaf to swing into and out of said opening and to move bodily along said upright members, brackets secured on the under side of said leaf and movable from positions in which they lie

flat against the latter to positions in which they extend downwardly, shoulders distributed along said uprights in position to engage said brackets when the latter extend downwardly from the leaf, and locking members mounted on the said leaf remote from the aforesaid end thereof and adapted to

be moved so as to project into said grooves to hold the leaf against swinging out of the opening in the standard. 10

In testimony whereof I sign this specification.

FRANK A. OSTERBERG.
